UNITED STATES PATENT OFFICE.

IRA F. GORDON, OF TRAVERSE CITY, MICHIGAN.

DESIGN FOR A SPRAYER-BODY.

SPECIFICATION forming part of Design No. 31,679, dated October 17, 1899.

Application filed January 16, 1899. Serial No. 702,375. Term of patent 3½ years.

To all whom it may concern:

Be it known that I, IRA F. GORDON, a citizen of the United States, residing at Traverse City, in the county of Grand Traverse and State of Michigan, have invented and produced a new and original Design for a Sprayer-Body, of which the following is a specification.

My invention relates to a novel and original design for a sprayer-body, and is illustrated in the accompanying drawing, in which the figure is a perspective view.

The leading feature of my said design consists in a cylindrical body having straight ends and a cylindrical barrel having a conical flattened end resting upon said body, as shown.

In the said drawing the reference-letter A indicates the cylindrical body, having straight

ends A', and the reference-letter B indicates the cylindrical barrel, having a flattened conical end B', resting upon body A.

My design presents a novel and distinguishing appearance.

Having thus described my invention, what I claim, and desire to secure by Design Letters Patent, is—

The design for a sprayer-body herein shown and described.

In testimony whereof I have hereunto set my hand in presence of two subscribing witnesses.

IRA F. GORDON.

Witnesses:

EDWARD TAGGART,
CHRISTOPHER HONDELINK.
